[57] CLAIM

The ornamental design for a towelette warmer, as shown and described.

DESCRIPTION

FIG. 1 is a top plan view of a towelette warmer showing my new design;

FIG. 2 is a right side elevational view thereof, the left side being a mirror of that shown;

FIG. 3 is a front elevational view thereof;

FIG. 4 is a rear elevational view thereof; and

FIG. 5 is a bottom plan view thereof.

The fragmentary criss-cross pattern shown in FIG. 1 is representative of a mesh-type screening and is understood to be repeated uniformly throughout the rectangular area.
